CAN OPENER

Francis H. Boyer, De Quincy, La.

Application June 19, 1953, Serial No. 362,761

2 Claims. (Cl. 30—22)

This invention relates to can openers and more particularly to a hand supported can opener for cutting around the edges of can tops.

It is among the objects of the invention to provide an improved can opener which has a longitudinally curved shank portion adapted to fit around the rim of a can and carrying a can cutting blade, a guide finger adjacent the blade and a fulcrum finger spaced from the guide finger and the blade for engaging a can rim to provide a fulcrum for forcing the blade into a can top; which includes a handle spaced along the shank from the blade and fulcrum finger a distance sufficient to provide ample leverage for easily forcing the blade through a can top; which is securely held in operative position on an associated can during the can opening operation; which has a bottle opening structure at the end of the handle remote from the can opening blade; and which is simple and durable in construction, economical to manufacture, easy to use, and effective and efficient in use.

Other objects and advantages will become apparent from a consideration of the following description and the appended claims in conjunction with the accompanying drawing, wherein:

Figure 1 is a top plan view of a can opener illustrative of the invention;

Figure 2 is a side elevational view of the can opener illustrated in Figure 1;

Figure 3 is a fragmentary perspective view of the can opener shown in operative association with a can also fragmentarily illustrated; and

Figure 4 is a fragmentary side elevational view of the can opener and associated can showing the manner in which the can opener is used to cut around the edge of the can top.

With continued reference to the drawing, the can opener comprises an elongated handle 10, preferably, but not necessarily, of circular cross sectional shape, having terminal formations of reduced diameter received in cylindrical ferrules 11 and 12. A can opener shank 14 formed from a metal strip of elongated, rectangular cross sectional shape with straight, substantially parallel side edges, has one end received in one end of the handle 10 and has the portion thereof projecting from the adjacent end of the handle arcuately curved longitudinally thereof to extend around the rim of a can. The end of the shank 14 remote from the handle 10 is provided with a longitudinally extending point formation 15 for puncturing can or other container tops.

A blade 16 is secured at one end to the shank 14 near the end of the shank remote from the handle 10 and extends across the width of the shank. This blade has straight and substantially parallel side edges 17 and 18 disposed substantially perpendicular to the longitudinal center line of the shank 14, a back or end edge 19 disposed substantially flush with the edge of the shank remote from the edge of the shank from which the blade projects, and a cutting edge 20 spaced from the

2

adjacent edge of the shank 14 and inclined relative to the adjacent edge of the shank with its end remote from the handle 10 nearer the shank than its end nearest the handle.

5 A guide finger 22 is secured at one end to the shank 14 at the end of the blade 16 remote from the handle and at the side of the shank opposite the blade and this guide finger extends from the shank in the same direction as the plate and perpendicular to the longitudinal center line of the shank, being parallel to the adjacent portion of the plate and spaced from the plate a distance equal to the thickness of the shank 14.

This guide finger is adapted to extend along the outer surface of a can with the blade inserted through the can top at the inner side of the can rim to guide the can opener around the can rim and firmly hold the can opener in operative position on the can, the distance between the guide finger and the adjacent surface of the blade being substantially equal to the thickness of a conventional can rim.

A fulcrum finger 24 is secured at one end to the shank 14 between the blade 16 and the adjacent end of the handle 10 and extends from the shank in the same direction as the blade 16 and the guide finger 22, being secured to the shank at the side of the latter opposite the blade 16 and disposed substantially perpendicular to the longitudinal center line of the shank. This fulcrum finger is somewhat shorter than the guide finger 22 having its end remote from the shank disposed adjacent the end of the cutting edge 20 of the blade 16 furthest from the shank 14 of the can opener. A tooth 25 is secured on the fulcrum finger 24 at the end of this finger remote from the shank 14 and on the side of the finger which contacts the adjacent surface of the shank. This tooth is directed toward the shank and inclined outwardly from the associated fulcrum finger so that its end nearest the shank is slightly spaced from the adjacent surface of the fulcrum finger to enable the tooth to engage under a can rim 26, as illustrated in Figure 4, to provide a fulcrum for forcing the cutting edge 20 of the blade 16 downwardly through the top 28 of a can when upwardly directed leverage is manually exerted on the handle 10 of the can opener with the can opener in operative position relative to an associated can.

With the blade disposed at the inner side of the can rim 26 and the guide finger 22 and fulcrum finger 24 disposed at the outer side of the can rim and with the shank 14 longitudinally curved substantially to the curvature of the can rim, the can opener will be firmly guided around the can rim and, by forcing the handle up and down and the blade forwardly as the can top is progressively cut away from the rim, the tool will be securely guided around the can rim and a smooth and even cut quickly made in the can top to separate the top from the associated rim.

A bottle opening structure 30 is disposed at the end of the handle 10 remote from the shank 14 and includes a shank portion 31 extending into the adjacent end of the handle through the terminal formation 12 of the handle, a lever 32 extending longitudinally from the shank 31 and a dog 33 offset from the shank at the proximal end of the lever 32 and adapted to engage under the edge of a crown cap on which the lever 32 is placed, so that leverage can be exerted on the cap by the handle 10 to force the cap off of the mouth of an associated bottle.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing

description, and all changes which come within the meaning and range of equivalency of the claims are, therefore, intended to be embraced therein.

What is claimed is:

1. A can opener comprising a handle; an elongated shank secured at one end to and extending from the handle, said shank being constant in width and thickness for substantially its full length; a blade secured at one end to and depending from the other end of the shank and disposed wholly at one side of the shank, said blade having at its other end a cutting edge inclined relative to the length of the shank; a guide finger secured to and depending from the shank transversely of the shank from the blade, said guide finger being disposed wholly at the other side of the shank and being spaced by the thickness of the shank from the blade for disposition of the guide finger and blade at opposite sides of a can rim bead and thickness of which is substantially equal to that of the shank; a fulcrum finger secured at one end to and depending from the shank at a location spaced longitudinally of the shank from the blade, between the blade and handle, said fulcrum finger being formed as a straight length of material extending normally to the length of the shank; and a tooth on the other end of the fulcrum finger directed toward the shank and inclined

5 outwardly from the fulcrum finger to engage under a can bead directly above which the shank is positioned.
2. A can opener comprising a handle, an elongated shank secured at one end to and extending from the handle, said shank being constant in width and thickness for substantially its full length, a blade secured at one end to and depending from the other end of the shank and disposed wholly at one side of the shank, said blade having at its other end a cutting edge inclined relative to the length of the shank, a fulcrum finger secured at one end to and depending from the shank at a location spaced longitudinally of the shank of the blade between the blade and handle, said fulcrum finger being formed as a straight length of material extending normally to 10 the length of the shank, and a tooth on the other end of the fulcrum finger directed toward the shank and inclined outwardly from the fulcrum finger to engage under a can bead directly above which the shank is positioned.
